WATERPROOF INCANDESCENT-ELECTRIC-LAMP SOCKET.

1,054,455.

Specification of Letters Patent. Patented Feb. 25, 1913.

Application filed June 19, 1911. Serial No. 633,917.

To all whom it may concern:

Be it known that I, EDWARD L. SCHNEIDER, of Syracuse, in the county of Onondaga, in the State of New York, have invented a certain new and useful Waterproof Incandescent-Electric-Lamp Socket, of which the following is a specification.

This invention has for its object the production of a water proof incandescent electric lamp socket which is particularly simple in construction, and highly efficient and durable in use; and it consists in the combinations and constructions hereinafter set forth and claimed.

15 In describing this invention reference is had to the accompanying drawing in which like characters designate corresponding parts in all the views.

Figure 1 is a vertical sectional view of this socket. Figs. 2 and 3 are opposite end views thereof.

1 is the body of the socket, the body being formed of insulation and having a recess 2 at one end, and substantially parallel wire 25 passages 3, 4 extending lengthwise thereof and opening into the inner end of the recess and preferably through the inner end wall thereof, the passages 3, 4 also opening through the end face of the body, and the 30 outer ends thereof are enlarged as at 5, 6 for a purpose hereinafter set forth.

7 is a screw threaded sleeve terminal located in the recess 2 and having an inturned flange 8 at its inner end abutting against the 35 inner end wall of the recess 2, the flange extending across the inner end of the passage 3 and having an opening 9 communicating with the wire passage 4.

10 is the central terminal of the socket, the 40 terminal 10 having an angular portion extending through the opening 9 and into the wire passage 4.

11 is a block of insulation located in the sleeve terminal 7 and abutting against the 45 flange 8 thereof, and having an opening 12 aligned with the opening 9 of the flange 8 and the wire passage 4, the opening 12 permitting the angular portion of the terminal

10 to pass through such block 11 of insulation.

The terminals are held to the body by a single clamping member consisting of a screw 13 preferably extending axially of the body of the socket and located in an axial passage 14, said screw 13 extending through the inner end of the central terminal 10, a central passage 15 in the block of insulation 11, through the axial passage 14 in the body 1 and into a nut 16 located in the outer enlarged end 17 of the passage 14.

The wires 18 and 19 extend into the passages 3, 4 respectively and are connected to the flange 8 of the sleeve terminal 7 and to the central terminal 10 in any suitable manner, as by soldering, and after the wires have 65 been placed in position, the passages 3, 4 and also the passage 14 are sealed against moisture by wax or cement poured into the enlarged ends 5, 6 and 17 of the wire passages and the passage 14.

This socket is particularly advantageous in that it is composed of minimum number of parts and has but one fastening member for securing all of the parts in assembled position.

What I claim is:

An incandescent electric lamp socket comprising a body formed with a recess at one end, and with substantially parallel wire passages opening into the inner end of the recess, a sleeve terminal having an inturned flange seated against the inner end wall of the recess, the sleeve terminal having an opening for communicating with one of the wire passages, a central terminal having an angular portion extending through said opening and into the wire passage with which said opening communicates, the body also having a lengthwise passage located between the wire passages, a block of insulation interposed between the flange and the inner end of the central terminal, a single fastening member extending through the central terminal, the block of insulation and the passage between the wire passages, and 95 wires in the passages respectively, the wires

being connected respectively directly to the flange of the sleeve terminal and to the portion of the central terminal extending into one of the wire passages, substantially as and for the purpose described.

In testimony whereof, I have hereunto signed my name in the presence of two at

testing witnesses, at Syracuse, in the county of Onondaga, in the State of New York, this 10th day of June 1941.

EDWARD L. SCHNEIDER.
